TOE PROTECTOR FOR HOSE

Filed Feb. 10, 1951

UNITED STATES PATENT OFFICE

2,687,528

TOE PROTECTOR FOR HOSE

Walter J. Paul, Vista, Calif., assignor to Richard Paul Inc., a corporation of California

Application February 10, 1951, Serial No. 210,373

1 Claim. (Cl. 2-61)

1
It is a fact that the hose worn by both men and women eventually wear out at their toe portions. This is frequently due to the fact that the toe-nails are not kept properly trimmed; the pressure of the tips of the unduly long nails finally cuts through the material of the hose at that point.

A principal object of the present invention is to provide a protective covering for the toes of ones' foot, to be worn within women's hose and men's socks, that will prevent the tips of their nails from coming into direct contact with the material of the hose, thereby substantially reducing the wear and tear on such hose, and lengthening their period of usefulness.

Toe protectors of this kind have been used heretofore, but it is found that in walking, the action and reaction of the toe protector and the shoe had a tendency to work the protector forwardly, so that its material would bunch up toward the tip of the toe, thereby causing discomfort to its wearer. Accordingly, another object of the invention is to give the toe protector a form that prevents its rear portion from creeping forward when its wearer is walking.

Further objects of the invention will be evident from a study of the drawing and the following specification.

The invention consists in the novel features of the foot protection device as disclosed herein.

A preferred embodiment of the invention is described in the following specification.

In the drawing:

Figure 1 is a side elevation of this toe protection device, and showing approximately the relation it has to one's foot when worn.

Figure 2 is a plan of a blank from which the toe protector illustrated can be most expeditiously formed.

Figure 3 is a side elevation of the toe protector as it would appear if laid flatly upon a supporting surface.

Referring now to Figures 1, 2, and 3, these figures illustrate a protection device for the toe. This device is illustrated in Figure 3 as though lying flatly upon a flat surface and is indicated by the reference number 27. It is composed of two side members, 43a and 43b, superposed upon each other and co-extensive with each other, preferably cut in one piece from the stock material and so that the side members are united integrally by a straight folded edge 28.

The side 27a of the protector is shown in Figure 1, and when the article is on the toe portion of one's foot the edge of the opening 30 at the

2
rear of the same is substantially straight, as viewed from the side, that is to say, this edge 31 will extend or lie substantially in a plane that is inclined to a vertical line. This is because the curved line or curved edge 32 of the article as illustrated in Figure 3 is of sufficient length measured from the point 33 to the point 34 to enable the article when on the foot, to extend well past the front of the metatarsal arch which would be located substantially in the vicinity of the dotted line 35 in Figure 1. When this point 34 is located beyond the metatarsal arch, it is found in practice that the action and reaction of the device to the movements of the foot in walking will not permit the rear portion of its sack form body to creep forwardly and toward the toe point 33.

The two edges 36a and 36b that form the edges of the opening 30 when this toe sack is lying flatly upon a flat surface, present the form of a lightly ogee curve extending from the point 37 down to the point 34. The upper portion 38 of this ogee curve is slightly concave on its outer side and the lower portion 39 is slightly convexly curved on its outer side, as illustrated in Figure 2. The edge of the opening is provided with an elastic cord sewed into a hem 40.

The blank 41 (see Fig. 2) that I prefer to employ in forming this toe protector has substantially the shape shown in Figure 2.

The two lower edges 42a of the blank as viewed in Figure 2 are only slightly concave toward their inner ends adjacent their point of intersection 45 on the axis 44, but are slightly convexly curved toward their outer portions as shown at 46, beyond which point they terminate respectively, in substantially straight extensions 47 that intersect the outer side edges 42 at the two points 48, at which points they form angles 49, respectively, approximating right angles.

The angle at the point 45 formed by the substantially straight extensions 42a is an obtuse angle 50. A blank of the form shown in Figure 2 enables the toe protector illustrated in Figure 3 to be readily formed from it.

These articles are preferably made from knit material, and in cutting out the blank for the toe it is preferably to have the general direction of the knitted threads parallel to the axis 44.

Obviously the blank for the toe protector could be made of two separate blanks sewed together along the line 44, that is, on a line corresponding to the line 44.

As will appear from Figures 1 and 3 of the drawing, when this toe protector is applied to

the wearer's foot the edge 28 is so much shorter than the length of the material between the point 33, and the point 34 under the toe portion of the foot, that the angle formed between the plane in which the edge 31 lies, and the vertical line 35 extending up from the front of the metatarsal arch is approximately 30 degrees. As the point 34 is located at the front portion of the downward bulge of the metatarsal arch, the tension in the material at the edge 31 will prevent the material located at the point 34, and its vicinity, from moving forward, because such movement would increase the tension in the edge 31. Another reason tending to prevent this, is the fact that the width of a normal foot at the location of the front metatarsal arch is greater than the width of the foot immediately to the rear of that arch.

Furthermore, with the point 34 remaining in a substantially fixed general location, back of the front metatarsal bulge, it will be evident that the upper end portion of the edge 31 will not move forwardly on the wearer's foot, because such movement at that point would also be resisted, for it would increase the tension in the edge 31. Many other embodiments of the invention may be resorted to without departing from the spirit of the invention.

I claim as my invention and desire to secure by Letters Patent:

A toe protection device comprising a sack-form body of flimsy material, said body having two side members of substantially equal size and form and symmetrical with respect to an upper axial line, each of said side members having a seam edge extending at an obtuse angle with a convex axial line from a common point with a convex bulge respectively adjacent to said common point,

each of said seam edges including a convex edge constituting an extension of said convex bulge, each of said side members also having a rear edge extending laterally at an obtuse angle with said axial line from a second common point, said rear edges being slightly concave adjacent said axial line and joining with said convex edges at approximately right angles, said rear edges being slightly convex adjacent said convex edges, a sole 10 seam joining said seam edges, the area of said body adjacent said right angles constituting a ball of the foot contacting portion, said side members being of only sufficient length to envelope a wearer's foot from the tips of his toes and extend rearwardly so that said ball contacting portion is disposed underneath the ball of the wearer's foot, said rear edges having an elastic cord therein and adapted to extend upwardly and forwardly in a plane inclined approximately 60 degrees from the horizontal from a point just rearward of the ball of the foot to a point just forward of the instep arch when applied to the wearer's foot.
